(57) **CLAIM**

The ornamental design for a front face of a vehicle wheel, as shown and described.

DESCRIPTION

FIG. 1 is a front view of a front face of a vehicle wheel, showing my new design;

FIG. 2 is a perspective view thereof;

FIG. 3 is a front view of a second embodiment of a front face of a vehicle wheel, showing my new design; and,

FIG. 4 is a perspective view of FIG. 3.

The broken lines showings are included for the purpose of illustrating environment and form no part of the claimed design.
